COUNTERBALANCING SASHES FOR VARIOUS METAL AND OTHER CASEMENTS

Filed Nov. 22, 1921

2 Sheets-Sheet 2

UNITED STATES PATENT OFFICE.

GEORGE W. LANCASTER, OF RICHMOND, VIRGINIA, ASSIGNOR TO PERFECTED WINDOW COMPANY, OF RICHMOND, VIRGINIA, A CORPORATION OF VIRGINIA.

COUNTERBALANCING SASHES FOR VARIOUS METAL AND OTHER CASEMENTS.

Application filed November 22, 1921. Serial No. 517,041.

To all whom it may concern:

Be it known that GEORGE W. LANCASTER, a citizen of the United States of America, residing at Richmond, in the county of 5 Henrico and State of Virginia, has invented new and useful Counterbalancing Sashes for Various Metal and Other Casements, of which the following is a specification.

The present invention has for its purpose

- 10 the provision of a plurality of counterbalancing sashes, either of metal or otherwise, preferably the former, with means connected to an upper sash and being shiftable into and out of engagement with the
- 15 lower sash and into and out of engagement with counterbalancing members, so that the uppermost and lowermost sashes may be counterbalanced, or the uppermost sash adjusted independently, while the two intermediate sashes are counterbalanced by each other.

Another purpose is to improve the construction and arrangement of sashes and counterbalancing means therefor, set forth,

- 25 illustrated and claimed in the copending application filed March 19, 1921, Serial No. 453,592.

In said copending application a member is shifted from the lowermost sash to a 30 counterbalancing member or weight and vice versa, but in this construction the shiftable means is grasped at the center, and it has been found that in moving the parts in the guides of the casement, frictional binding 35 may more or less occur.

Therefore the present invention aims to avoid this possibility, by providing a shifting bar, shiftable from engagement with the lowermost sash, into engagement with the 40 counterbalancing members or weights and vice versa, the bar being so arranged that it can be grasped by the operator at any point throughout its length.

Still another purpose, is the provision of 45 channel guides for the sashes, and channel guides for the counterbalancing weights, and channel guides for the operating transverse bar, the guides for the operating transverse bar are cut away at their lower portions, to 50 permit the transverse bar to be shifted from the counterbalancing weights to engagement with the lowermost sash and vice versa, in order to adjust the uppermost and lowermost sashes, or the uppermost sash independently, for the purpose of ventilation.

While the design and construction at present illustrated and set forth are deemed preferable, it is obvious that as a result of a reduction of the invention to a more practical form for commercial purposes, the invention may be susceptible of changes, and the right to these changes is claimed, provided they are comprehended within the scope of what is claimed.

The invention comprises further features 60 and combination of parts, as will be hereinafter set forth, shown in the drawings and claimed.

In the drawings:—

Figure 1 is a view in perspective of the 70 lower portion of a window casement, showing the application of the counterbalancing sashes and the operating means;

Figure 2 is a transverse sectional view through one side of the window; 75

Figure 3 is a vertical sectional view on line 3—3 of Figure 1, but showing the entire casement and the entire set of counterbalancing sashes;

Figure 4 is a sectional view on line 4—4 80 of Figure 3; and

Figure 5 is a detail perspective view of one end of the transverse movable bar or member, for adjusting the lowermost and uppermost sashes, or the uppermost sash 85 independently.

Referring to the drawings, 1 designates a window casement, constructed of any suitable material preferably sheet metal. This casement is provided with a plurality of 90 guides 2, 3, 4, and 5, for the uppermost and lowermost sashes 6 and 7 and the intermediate sashes 8 and 9. The intermediate sashes are operatively connected by the cord or cable 10, passing over the pulley 11, for counterbalancing them. The upper part of the casement has mounted therein pulleys 12, which are engaged by the cord or cable 13, one end of which is connected at 14 to the uppermost sash 6. 100

The casement is provided with additional guides 15 and 16 arranged perpendicularly at the sides of the casement. The casement is also provided with guides 17, in which counterbalancing members or weights 18 are mounted. The wall 19 separating the guides 15 and 16 has its lower end cut away as at 20.

Mounted in the casement between its perpendicular sides is an operating bar 21, 110

which has enlargements 22 at its opposite ends. The enlargements may be any suitable shape, preferably as shown, and are provided with reduced extensions 23, which are designed to engage and operate in the guides 15 or in the guides 16, of the opposite sides of the casement. When the operating bar is shifted toward the lowermost sash, the reduced extensions 23 will operate in the guides 16. If shifted away from the lowermost sash, then the reduced extensions 23 will operate in the guides 15. The lower rail of the lowermost sash is provided with projections or pins 24, which are axially aligned with the projections or pins 25, which are carried by the weights or counterbalancing members 18. Immediately adjacent the reduced extensions 23, the enlargements 22 of the operating bar are provided with openings 26, which may receive the projections 24 or the projections 25. It will be noted that when the operating bar 21 is shifted toward the lowermost sash or toward the weights or counterbalancing members, the extensions 23 pass through the cut away portions 20, so as to be in a position to engage the guides 15 or the guides 16. When the operating bar 21 is moved toward the lower rail of the lowermost sash, the pins or projections 24 will enter the openings 26, then the operating bar 21 will move with the lowermost sash, and since the cords or cables 13 are connected at 27 to the enlargements of the operating bar, the lowermost sash will counterbalance with the uppermost sash. In other words when the operating bar is connected to the lowermost sash and said sash is raised, the uppermost sash is lowered.

When the operating bar is shifted toward the counterbalancing members or weights 18, the projections or pins 25 will enter the openings 26, in which case the weights or counterbalancing members 18 will move with the operating bar, and since the bar is connected to the uppermost sash of the cords 13, then the uppermost sash may be lowered independently. It will be noted that the hand grasping portion 28 of the operating member or bar is offset from the enlargements, so as to permit the bar to be easily grasped by the operator.

It will be noted that the various sashes are interengaged as at 29, to correspond with similar interconnections as disclosed in the above mentioned copending application.

Also the lower rail of the lowermost sash is engaged by a spring tensioned locking pin 30, similar in construction to that disclosed in said copending application, therefore it is deemed unnecessary to describe the lock in detail.

The invention having been set forth, what is claimed as being useful is:

1. In a window structure, the combination

with a casement having opposite perpendicular guides, of uppermost and lowermost sashes, mounted in certain sets of the guides, counterbalancing devices mounted in another set of the guides, spaces connecting the lower ends of certain sets of the guides between the guides for the sashes and those for the counterbalancing devices, an operating device mounted to move selectively in any of the connected sets, by shifting it through said spaces, means operatively connecting said device and the uppermost sash, and means for detachably and operatively connecting said device with the lowermost sash, or the counterbalancing devices, whereby the lowermost and uppermost sashes may be counterbalanced in their movements, or the uppermost sash moved independently and counterbalanced with the counterbalancing devices.

2. In a window structure, a casement having two opposite perpendicular sets of guides including dividing walls, the lower ends of said walls being cut away causing openings to be formed connecting the lower ends of said guides, an operating member shiftable through said openings, whereby the operating member may slide in either of said connected sets of guides, said casement having additional guides, counterbalancing devices in said additional guides, upper and lowermost sashes mounted for vertical movement in said additional guides, and operative connections between the uppermost sash and the operating member, said operating member adapted to operatively connect with the lowermost sash or the counterbalancing devices, whereby the lowermost sash may be counterbalanced with the uppermost sash, or the uppermost sash may be counterbalanced with the counterbalancing devices.

3. In a window structure, a casement having two opposite perpendicular sets of guides including dividing walls, the lower ends of said walls being cut away to cause passages to be formed connecting the corresponding ends of said guides, the casement having additional guides, counterbalancing devices movable in said additional guides and provided with a set of projections, upper and lowermost sashes mounted for vertical movement in the casement the lowermost sash having a set of projections, an operating bar movable through said passages for operating in either set of the first mentioned guides and having openings at its ends to receive the projections of either set thereof, whereby the operating bar may move with the counterbalancing devices or with the lowermost sash, and means operatively connecting said bar and the uppermost sash.

4. In a window structure, a casement having two opposite perpendicular sets of guides including dividing walls, the lower ends of said walls being cut away to cause

passages to be formed connecting the corresponding ends of said guides, the casement having additional guides, counterbalancing devices movable in said additional guides 5 and provided with a set of projections, upper and lowermost sashes mounted for vertical movement in the casement, the lowermost sash having a set of projections, an operating bar movable through said passages for 10 operating in either set of the first mentioned guides and having openings at its ends to receive the projections of either set thereof, whereby the operating bar may move with the counterbalancing devices or with the 15 lowermost sash, and means operatively connecting said bar and the uppermost sash, said operating bar having enlargements at its ends provided with reduced extensions to engage either set of perpendicular guides, 20 said bar having a hand grasping portion offset from the enlargements, whereby the operator may easily grasp the same.

5. In a window structure, a casement having two opposite perpendicular sets of 25 guides including dividing walls, the lower ends of said walls being cut away to cause passages to be formed connecting the corresponding ends of said guides, the casement

having additional guides, counterbalancing devices movable in said additional guides 30 and provided with a set of projections, upper and lowermost sashes mounted for vertical movement in the casement, the lowermost sash having a set of projections, an operating bar movable through said passages for 35 operating in either set of the first mentioned guides and having openings at its ends to receive the projections of either set thereof, whereby the operating bar may move with the counterbalancing devices or with the 40 lowermost sash, and means operatively connecting said bar and the uppermost sash, said operating bar having an offset hand grasping portion, whereby the operator may easily move the same, and means for locking 45 the lowermost sash when lowered, adapted to prevent opening the lowermost sash when the uppermost sash is opened by operating the bar.

In witness whereof, in the presence of two 50 witnesses, the inventor's signature is hereunto affixed.

GEORGE W. LANCASTER.
